The ornamental design for a sensor enclosure assembly for a hose, as shown and described.

DESCRIPTION

FIG. 1 is a top perspective view of a sensor enclosure assembly for a hose showing my new design.

FIG. 2 is a bottom perspective view of the sensor enclosure assembly for a hose of FIG. 1.

FIG. 3 is a left elevation view of the sensor enclosure assembly for a hose of FIG. 1.

FIG. 4 is a right elevation view of the sensor enclosure assembly for a hose of FIG. 1.

FIG. 5 is a top plan view of the sensor enclosure assembly for a hose of FIG. 1.

FIG. 6 is a bottom plan view of the sensor enclosure assembly for a hose of FIG. 1.

FIG. 7 is a front elevation view of the sensor enclosure assembly for a hose of FIG. 1; and,

FIG. 8 is a back elevation view of the sensor enclosure assembly for a hose of FIG. 1.

The broken lines illustrate portions of the sensor enclosure assembly for a hose which form no part of the claimed design.
